[57] CLAIM

The ornamental design for a rechargeable lantern, as shown and described.

DESCRIPTION

FIG. 1 is a top plan view of a rechargeable lantern showing my new design;

FIG. 2 is a bottom plan view thereof;

FIG. 3 is a front elevational view thereof;

FIG. 4 is a rear elevational view thereof; and,

FIG. 5 is a right side elevational view, the left side elevational view not shown as it is substantially the same as the right side elevational view.
